UNITED STATES PATENT OFFICE.

CARL A. BJORNSSON, OF WELLSVILLE, NEW YORK, ASSIGNOR TO McEWEN BROS., OF WELLSVILLE, NEW YORK, A CORPORATION OF NEW YORK.

ATOMIZER FOR OIL-ENGINES.

1,255,380.

Specification of Letters Patent. Patented Feb. 5, 1918.

Application filed November 22, 1916. Serial No. 132,857.

To all whom it may concern:

Be it known that I, CARL A. BJORNSSON, a subject of the King of Sweden, residing at Wellsville, in the county of Allegany and State of New York, have invented certain new and useful Improvements in Atomizers for Oil-Engines, of which the following is a specification, reference being had to the accompanying drawings.

10 This invention relates to internal combustion oil engines and has for its primary object to increase the efficiency in operation and consequently the working energy developed in engines of that type wherein an atomized fuel is burned in the combustion chamber by the temperature of highly compressed air into which the fuel is liberated.

15 The invention has for a particular item of improvement, a fuel atomizing valve of relatively simple construction, through the medium of which the liquid fuel is delivered in a very finely atomized state and under high pressure to the combustion chamber.

20 I also have in view the provision of an improved fuel atomizer possessing the above noted advantageous features and capable of utilizing unrefined, hydrocarbon oils as fuel so that the operating cost will be relatively small, the several parts employed being 25 simple in their construction, not liable to get out of order, and highly positive and reliable in practical operation.

With the above and other objects in view, my invention consists in the novel features of 30 construction, combination and arrangement of parts to be hereinafter more fully described, claimed and illustrated in the accompanying drawings, in which,

35 Figure 1 is a longitudinal section of the fuel atomizing valve;

40 Fig. 2 is a section taken on the line 2—2 of Fig. 1.

45 In oil engines of that type wherein the fuel charge is fired by the heat of compression clean, atmospheric air is drawn by suction into the engine cylinder in the movement of the piston in one direction, the valve 25 being positively opened. On the reverse stroke of the piston, this air is very highly compressed within the relatively restricted 50 dimensions of the combustion chamber. This pressure is sufficient to increase the temperature of the air to such a degree that it will instantly ignite the finely commi-

nuted liquid fuel liberated therein. It is, therefore, the purpose of my improved valve which I shall now describe, to reduce the relatively heavy fuel oil to a state of extremely fine sub-division, and deliver the same in a predetermined and exact quantity 60 through the spray nozzle into the high temperature, compressed body of air, so that instant ignition of the fuel is assured.

Referring now in detail to the drawings, 65 34 designates a body of any preferred form, which is longitudinally bored, as at 35. The opposite ends of this bore 35 are enlarged and threaded, and a detachable nipple 36 is engaged in one of said threaded ends of the bore and connected by means of the pipe 37 to the air compressor. The inner end of the nipple is spaced from the reduced, central portion of the bore 35 to afford a relatively large collecting chamber 38 between the nipple and the valve head 39 formed upon the 70 reduced end 41 of the longitudinally movable valve rod 40. This valve head 39 is normally in tight engagement upon the valve seat 42 and disposed in spaced relation to the inner end of the nipple 36. In 75 the other threaded end of the bore 35, the exteriorly threaded end of a sleeve 43 is engaged, and within the bore of said sleeve the valve rod 40 is movably disposed, said rod having spaced packing grooves 44 to 80 effectually prevent the leakage of the air or fuel around the valve rod. The sleeve and valve rod are inclosed within an outer casing 45 which is bolted or otherwise rigidly fixed at one of its ends to the body 85 34, said body in turn being suitably secured to the face of the cylinder head 17. The casing 45 is provided intermediate of its ends with an internal flange 46 affording a support for the end of the sleeve 43. A 90 cylindrical head 47 is slidably engaged in the outer end of the casing 45 and has a central, longitudinally projecting boss 48 within which the valve rod 40 snugly fits. A coiled expansion spring 49 is disposed 95 within the casing 45 around the valve rod, and bears at one of its ends against the flange 46 and has its other end seated within the sliding head 47. The valve rod is provided with a reduced, threaded extension 50 100 upon which a nut 51 and sleeve 52 are engaged, said nut being interposed between the sleeve and the end of the boss 48.

The body 34 is also centrally formed with an oil receiving chamber 53 in communication with the center of the bore 35. A sectional valve casing 54 is fitted within the body 34, one of said sections having orifices 55 through which the oil is forced under pressure into the chamber 53. The other valve section constitutes a cage for the ball check valve 56 which prevents backflow of 10 the oil through the bore of the nipple 57 to which the supply pipe 58, extending from the fuel pump, is connected.

A laterally extending, cylindrical arm 59 is integrally formed with the body 34 and 15 is adapted to be fitted within the central opening in the front side of the detachable cylinder head which is in communication with the combustion chamber 18. This arm is longitudinally bored, as at 60, the axis 20 of said bore being out of coinciding relation with the longitudinal axis of the valve rod 40. The bore 60, at its inner end, terminates in spaced relation to the bore 35 extending at right angles thereto, and within 25 this inner end of the bore 60 a flanged disk 61 is seated. A sleeve 62 is fitted within the bore 60 and has a reduced end 63 engaged within the annular flange on the disk 61. This sleeve 62 has a central, longitudinally extending mixing chamber 64 gradually flaring or increasing in diameter to the outer end of said sleeve. The face of the disk 61 next adjacent to the reduced end of the sleeve 62, has an annular recess 65 there- 30 in of greater diameter than the end of the chamber 64, and a plurality of oblique fuel inlets 66 lead from this recess to an annular groove or channel 67 formed in the periphery of the disk 61. This disk has an 35 air inlet opening 68 which is in registering relation with an air passage 69 in the body 34 extending substantially in tangential relation to the bore 35 at the lower side thereof. A second orifice 70 permits the passage 40 of oil from the collection chamber 53 into the fuel inlets 66 in the disk 61. In order to conveniently clean the oil collection chamber and remove sediment therefrom, a screw 71 is threaded in the body 34 and has 45 a needle point 72 for engagement in the outer end of an orifice 73 communicating with said collection chamber in opposed relation to the orifice 70. A downwardly inclined duct 74, extending through the body 50 34, is in communication with the outer end of the orifice 73.

For the reason to be presently related, the air inlet opening 68 in the disk 60 and the air passage 69 are of somewhat less diameter 55 than the inner end of the mixing chamber 64 through the sleeve 62. A spray nozzle 75 is threaded in the end of the arm 59 and has a central passage or bore 76 of relatively small diameter flaring at one end, as at 77, 60 to approximately the same diameter as the

outer end of the mixing chamber 64. The end face of this nozzle opposed to the combustion chamber, has a relatively wide, flaring, cylindrical passage 77 communicating at its base or smaller end with the bore 76. 70

The fuel valve rod 40 is actuated through the medium of a bell crank lever 78 which is loosely fulcrumed upon a fixed supporting shaft 79. One arm of the bell crank lever is upwardly extended above the shaft 79 75 and at a slight lateral inclination, and provided with a raised plate 80 having suitable indicating means theron. This upper end of the lever arm is also formed with a chambered, cylindrical boss 81. A rod 82 is slidably disposed through said chamber and has a reduced portion extending through an opening in the end wall of the chamber to which a diametrically extending key 83 is fixed. The end face of the boss 81 is grooved, 80 as at 84, to receive the ends of this key. The rod 82 is provided with a slightly reduced end portion upon which an operating element 85 is suitably fixed. In the present instance I have shown this element as consisting of a conveniently shaped hand grasp having a sleeve snugly fitting within the chambered boss 81. A coil spring 86, disposed within said chamber, acts against said sleeve and normally urges the rod 82 outwardly so that in one position of said rod, the ends of the key 83 will be held within the groove 84. 90

The other arm of the bell crank lever 78 extends forwardly and has a roller 87 suitably mounted thereon for engagement by a cam 88 fixed upon the cam shaft 89. 100

From the above description, the operation of the fuel atomizing valve will be clearly understood. The rod 82 must first be forced 105 longitudinally against the action of the spring 86 to disengage the key 83 from the groove 84. The rod is then given a quarter turn so that the key will be held in its extended position with relation to the boss 81. 110 Thus, in the rotation of the cam shaft, the bell crank lever 78 is actuated to intermittently shift the valve rod 40 inwardly against the action of the spring 49. It is to be remembered that the fuel is being supplied during the operation of the engine, from the pump under pressure, upwardly past the ball valve 56 and into the collection chamber 53. The fuel pump delivers the fuel into chamber 53 and orifices 70 and 73, 115 the combined capacity of which is equal to the volume of fuel delivered upon each maximum stroke of the fuel pump plunger. The fuel is delivered into the chamber 53 during the suction stroke of the engine and, 120 consequently, is not under pressure. The pressure in the chamber 53 is subject to the variable pressures in the combustion chamber, and it is the purpose of the ball check valve 56 to restrict these pressures to the 125 130

limit of said chamber and passages which directly communicate with the combustion chamber.

When the fuel valve rod 40 is actuated, the fuel which has been deposited in the duct 70 is subjected to the high injection air pressure, and this pressure prevails upon the oil in duct 70 while the air is flowing through the orifice 69. The air expands slightly upon entering the mixing chamber 64 of the sleeve 62 which is of slightly greater diameter than the air inlet opening 68. This decrease in pressure of the air permits the fuel to be forced through duct 70 and through the obliquely inclined duct 66 where the several fine fuel jets are met by the air entering the mixing chamber 64. The fuel is thus atomized and conducted by the air through the chamber 64 to the spraying nozzle 75. Owing to the contracted bore 76 of this nozzle, there will be a material increase in pressure and velocity so that when the mixture of air and fuel oil finally leaves the nozzle, it is in a highly atomized state and expands throughout the combustion chamber. In this manner, the oil is supplied in a thoroughly atomized condition and in uniform quantity to the combustion chamber. The valve construction above referred to has been found very satisfactory and efficient in practical operation. When necessary, the operation of this valve may be momentarily suspended by simply turning the rod 82 so that the ends of the key 83 will seat within the groove 84. In this position of the key, the throw of the bell crank lever under the action of the cam 88 is insufficient to cause an operative movement of the air control valve.

From the foregoing description, taken in connection with the accompanying drawing, the construction, manner of operation, and several advantages of my improved fuel atomizer will be clearly and fully understood. By finely sub-dividing the fuel oil in the manner above pointed out, I am enabled to use the lower grades of hydrocarbon oils for use in oil engines with very satisfactory results and with the realization of considerable economy in the operation of the engine. It will be appreciated that as the device consists of very few simply constructed parts, it is, therefore, positive and reliable in its operation. The invention may also be manufactured and used in connection with liquid fuel engines of different constructions at relatively small cost.

I have herein illustrated a construction of my improved atomizer which I have found to be entirely practical, but it will, of course, be manifest that in the adaptation of the device to engines of this type employed for various commercial purposes, it may be found desirable to resort to certain structural modifications in the several detail parts

thereof. It is, therefore, to be understood that I do not desire to be limited to the precise form and arrangement of the various elements as herein set forth, but reserve the privilege of resorting to all such legitimate changes as may be fairly embodied within the spirit and scope of the invention as claimed.

Having thus fully described my invention, what I desire to claim and secure by Letters Patent is:—

1. An atomizer for internal combustion engines including a body having an oil collection chamber and fuel and air supply connections thereto, a valve controlling the admission of compressed air into said chamber, said body being further provided with an unobstructed mixing chamber, and means interposed between the mixing chamber and the oil collection chamber and at all times affording communication therebetween for the separate delivery of oil and compressed air from the collection chamber into the mixing chamber.

2. An atomizer for internal combustion engines including a body having an oil collection chamber and fuel and air supply connections thereto, a valve controlling the admission of compressed air into said chamber, said body being further provided with an unobstructed mixing chamber, and means interposed between the mixing chamber and the oil collection chamber and at all times affording communication therebetween for the separate delivery of oil and compressed air into the mixing chamber and at relatively different pressures.

3. An atomizer for internal combustion engines including a body having an oil collection chamber and fuel and air supply connections thereto, a valve controlling the admission of compressed air into said chamber, said body being further provided with an unobstructed mixing chamber, and means interposed between the mixing chamber and the oil collection chamber to deliver oil under pressure in a plurality of jets into the mixing chamber and also to deliver a portion of the air from the collection chamber under relatively reduced pressure into the mixing chamber and in angular relation to the oil jets.

4. An atomizer for internal combustion engines including a body having air and fuel connections disposed at right angles to each other, said body being also provided with an unobstructed mixing chamber extending at right angles to said air and fuel connections, said body having spaced air and fuel passages communicating with said chamber, and a valve controlling the supply of compressed air for delivering the fuel and air under pressure through the passages and into the mixing chamber.

5. An atomizer for internal combustion

engines including a body provided with an oil collection chamber and air and fuel supply connections, an angularly projecting arm on said body, a member removably mounted in said arm and having a mixing chamber, said body being provided with spaced fuel and air passages, means interposed between the mixing chamber and said passages to direct fuel under pressure in a plurality of jets into the mixing chamber and to direct the air axially into the chamber at an angle with respect to the oil jets, a valve controlling the supply of compressed air to the oil collection chamber, and a spray nozzle mounted in the end of said arm.

6. An atomizer for internal combustion engines including a body having an injecting nozzle and an air passage, a disk interposed between the end of the nozzle and the air passage and having a central opening constituting a continuation of the air passage which is in alinement with the nozzle bore, said body being further provided with an oil collection chamber and a check valve 25 to prevent the return flow of oil from said chamber, said disk having an annular channel in its periphery in communication with the oil collection chamber and a series of angularly extending oil ducts leading from said channel to the face of the disk opposed to the nozzle bore, and a normally closed valve controlling the supply of compressed air to said passage.

7. An atomizer for internal combustion engines including a body having an injecting nozzle, an oil collection chamber and an air passage disposed in tangential relation to said chamber, a disk interposed between said air passage and the end of the nozzle and 40 having a central opening registering with

the passage of the nozzle bore, means for preventing the return flow of oil from the collection chamber, said disk being provided with a channel in its periphery and the valve body having a passage connecting 45 said channel to the base of the oil chamber, the disk being further provided with angular oil ducts leading from said channel to the face of the disk opposed to the nozzle, and a normally closed valve controlling the 50 supply of compressed air to the air passage.

8. An atomizer for internal combustion engines including a body having an oil collection chamber and an air passage extending at right angles to said chamber and in 55 communication therewith, said passage being provided with a valve seat, oil inlet and supply pipes respectively connected to the collection chamber and air passage, an injecting nozzle, a disk interposed between the 60 nozzle and the air passage and having a central opening coinciding with the nozzle bore but of smaller diameter than said bore, the valve body being further provided with a bypass in communication with the base of 65 the oil chamber, said disk having an annular channel in its periphery with which the bypass communicates, a plurality of ducts leading from said channel to the end of the opening in the disk which is opposed to the nozzle 70 bore, a normally closed valve engaged upon said seat, and means for intermittently opening the valve.

In testimony whereof I hereunto affix my signature in the presence of two witnesses. 75

CARL A. BJORNSSON.
